Patented July 2, 1929.

Des. 78,876

UNITED STATES PATENT OFFICE.

EDWIN BURKE, OF CHICAGO, ILLINOIS, ASSIGNOR TO MAXWELL-BURKE, INCORPORATED, OF CHICAGO, ILLINOIS, A CORPORATION OF ILLINOIS.

DESIGN FOR A KITCHEN CABINET OR SIMILAR ARTICLE.

Application filed December 10, 1927. Serial No. 24,434. Term of patent 3½ years.

To all whom it may concern:

Be it known that I, EDWIN BURKE, a citizen of the United States, and resident of the city of Chicago, in the county of Cook and State of Illinois, have invented a new, original, and ornamental Design for a Kitchen Cabinet or Similar Article, of which the following is a specification, reference being had to the accompanying drawing, forming a part thereof.

On the drawings:

I claim:

The ornamental design for a kitchen cabinet or similar article as shown.

EDWIN BURKE.
